(57) **ABSTRACT**

‘SH-4199’ is a hybrid dessert banana variety that has a dwarf
stature, is resistant to black Sigatoka, and produces high-
quality fruit.

6 Drawing Sheets

1

Latin name of the genus and species of the plant claimed:
This tetraploid plant has only *Musa acuminata* in its pedigree.
This tetraploid hybrid is the product of an inter-specific cross
between one diploid (AA) and two triploid (AAA) cultivars.
Its Latin name is *M. acuminata* group (AAAA), representing four genomes of the *M. acuminata*.

Variety denomination: ‘SH-4199’.

**STATEMENT REGARDING FEDERALLY
SPONSORED RESEARCH OR DEVELOPMENT**

Not applicable.

BACKGROUND OF THE INVENTION

This invention relates to a new and distinctive hybrid banana plant variety named ‘SH-4199’. This new hybrid variety was the result of a field cross performed in 2016 in La Lima Cortés, Honduras, between ‘SH-4168’ x ‘SH-3142’ (Both unpatented). The female parent ‘SH-4168’ is a medium triploid plant (AAA) “Cavendish type” tolerant to Black Sigatoka leaf spot disease (*Mycosphaerella fijiensis*), developed from accessions and breeding lines a germplasm bank. The pedigree of ‘SH-4168’ is ‘ITC-570’ (‘Williams’) x ‘Novak’, both belonging to the Cavendish group.

The male parent, ‘SH-3142’, is diploid (AA), resistant to burrowing nematodes (*Radopholus similis*), Sigatoka leaf disease (*Mycosphaerella fijiensis*), and *Fusarium* wilt (*Fusarium oxysporum* f. sp. *cubense* Race 1 and 4). The pedigree of ‘SH-3142’ is ‘AVP-357’ and ‘II-30’ → ‘III-133’ x ‘SH-77’ → ‘SH-1734’ x ‘II-155’ → ‘SH-3142’. ‘AVP-357’ is a *Musa acuminata* subsp. *malaccensis* diploid (AA) from the two original parental lines, and the ‘II-30’ is a *Musa acuminata* subsp. *errans* diploid (AA).

‘SH-4199’ was selected in 2018 from several first-generation seedlings from the cross between ‘SH-4168’ and ‘SH-3142’. It was chosen as a tetraploid hybrid maintaining the “Cavendish type” stature and taste of its female parental

2

line and producing bunches of 20 kilograms with fruits of the same quality as the mother ‘SH-4168’. Furthermore, it presents the black Sigatoka leaf spot disease (*Mycosphaerella fijiensis*) resistance of his ‘SH-3142’ male parental line. 5 ‘SH-4199’ was asexually reproduced by corms by the breeder in La Lima Cortés, Honduras. All plants and fruit run true to the initially selected plant and are identical in all aspects.

The hybrid ‘SH-4199’ has many similarities with its 10 mother, ‘SH-4168’. These similarities include the plant’s size, the shape of the cluster, the distribution of the leaves, the shape of the fingers, and the flavor. However, ‘SH-4199’ is more resistant to black Sigatoka (*Mycosphaerella fijiensis*) than ‘SH-4168’. It is possible that ‘SH-4199’ inherited this resistance from its parent ‘SH-3142’, which is a tall plant with a large bunch and an unpleasant flavor and is very different from ‘SH-4199’. ‘SH-4199’ differs from commercial varieties such as ‘Grand Naine’ or ‘Williams’ in fruit taste and bunch size. Compared to ‘Grand Naine’ or ‘Williams’, ‘SH-4199’ may not have the same commercial value, but it has the potential to contribute to the development of better varieties.

BRIEF SUMMARY OF THE INVENTION

‘SH-4199’ is a hybrid dessert banana variety with a dwarf stature, is resistant to black Sigatoka, and produces high-quality fruit.

BRIEF DESCRIPTION OF THE PHOTOGRAPHS

The figures describe the characteristics of the ‘SH-4199’ hybrid banana variety. The color shown in the photographs is as nearly accurate as reasonably possible in this type’s color representation.

FIG. 1 shows the typical appearance of a plant at ten (10) months old;

FIG. 2A-B show blots of the petiole base (A) and a petiole canal (B);

FIG. 3A-C shows the shape of a leaf blade base (A) and leaf upper (B) and lower (C) surfaces;

FIG. 4A-B shows water suckers (A) and leaves without blots (B);

FIG. 5 shows a typical fruit bunch;

FIG. 6 shows a male bud;

FIG. 7A-C shows bracts of male buds;

FIG. 8A-C shows compound tepals (A and B) and free tepals (C) lobes;

FIG. 9A-B shows the style shape (A) and an ovary (B);

FIG. 10 shows a male flower;

FIG. 11 shows rowed ovules; and

FIG. 12 shows a typical second hand.

DETAILED BOTANICAL DESCRIPTION

The following is a detailed botanical description of the new variety 'SH-4199'. The report is from plants located in La Lima, Cortés, Honduras that were evaluated in 2023. The descriptions concord with the internationally standardized "Descriptors for Banana (*Musa* spp.)" elaborated by IPGRI-INIBAP/CIRAD, 1996, and the U.K's Royal Horticultural Society's Colour Chart, 2001. The 'SH-4199' plant and its fruit may vary slightly from the detailed descriptors shown below due to cultural practices, soil types, and climatic conditions under which the variety may be cultivated.

Leaf habit	Intermediate	Color of cigar leaf dorsal surface	Green (139B, RHS)
Dwarfism	Dwarf type	Blots on leaves of water suckers	Without blots
Pseudostem length	2.02 m	Peduncle length	61-70 cm
Pseudostem diameter	67 cm	Empty nodes on the peduncle	Two or more
Pseudostem height	2.1 to 2.9 meters	Peduncle width	7-12 cm
Pseudostem aspect	Robust	Peduncle color	Green (136B, RHS)
Pseudostem color	Yellow-Green (146D, RHS)	Peduncle hairiness	Very hairy, short hairs (similar to velvet touch)
Pseudostem appearance	Shiny (Not waxy)	10 Bunch length	66 cm
The predominant underlying color of the pseudostem	Greyed-red (179D, RHS)	Bunch diameter	77 cm
Pigmentation of the underlying pseudostem	Greyed-Red (180A, RHS)	Number of hands per bunch	12
Sap color	Milky (4D, RHS)	Bunch position	Hanging vertically
Wax-on leaf sheaths	Very few waxes	Bunch shape	Truncated cone shape
Number of suckers	3-4	Bunch appearance	Very Compact
Development of suckers	>1/4 and <3/4 of the height of the parent plant	15 Flowers that form the fruit	Female
Position of suckers	Close to parent (vertical growth)	Fruits	Biseriate
Blots at the petiole base	Extensive pigmentation	Rachis type	Present and male buds may be degenerated or persistent
Blots color	Greyed-Brown (N199A, RHS)	Rachis position	With a curve
Petiole canal leaf III	Straight with erect margins	Rachis appearance	Bare
Petiole margins	Winged and clasping the pseudostem	Male bud type	Normal (present)
Wing type	Dry	Male bud shape	Ovoid
Petiole margin color	Without color	Male bud size	21 to 30 cm
Edge of petiole margin	Colourless (Without a color line along)	Bract base shape	Large shoulder
Petiole margin width	>1 cm	Bract apex shape	Intermediate
Leaf blade length	221 to 260 cm	Bract imbrication	Young bracts considerably overlap
Leaf blade width	81 to 90 cm	25 Color of the bract external face	Purple (N79A, RHS)
Petiole length	51 to 70 cm	Color of the bract internal ace	Greyed-Red (181A, RHS)
Color of the leaf's upper Surface	Green (136A, RHS)	Color of the bract apex	Tinted with yellow (discolored) (17A, RHS)
Appearance of leaf upper surface	Dull	Color stripes on the bract	Without discolored lines (not ridges) on the external face
Color of the leaf's lower surface	Green (N138B, RHS)	30 Bract scars on rachis	Very prominent
The appearance of the leaf lower surface	Dull	Persistence of the bracts of the rachis	Moderate
Wax on leaves	Very wax	Fading of color on bract base	Color homogenous
The insertion point of the leaf blade on the petiole	Asymmetric	Male bract shape	Ovate
The shape of the leaf blade base	One side is rounded, one-pointed.	Male bract lifting	Lifting one at a time
Leaf corrugation	Very corrugated	35 Bract behavior before falling	Revolute (Rolling)
Color of midrib dorsal surface	Green (141C, RHS)	Wax on the bract	Moderately wax
Color of midrib ventral surface	Yellow-green (144B, RHS)	Presence of grooves on the bract	Strongly grooved

US PP36,079 P2

5

-continued

Color of the flesh of the fruit	Creamy (8D, RHS)
Longitudinal ridges of the fruit	weak
Transverse section of fruit	Slightly ridged
Fruit apex	Bottle-necked
Remains of flower relicts at the fruit apex	Persistent style
Fruit pedicel length	21-23 mm
Fruit pedicel width	10-12 mm
Pedicel surface	Hairless
Fusion of pedicel	Very partially or no visible sign of fusion
Immature fruit peel color	Green (139C, RHS)
Mature fruit peel color	Yellow-orange (15B, RHS)
Fruit peel thickness	1.5-2 mm
Adherence to the fruit peel	Fruit peels easily
Cracks in fruit peel	Without Cracks
Pulp in fruit	With pulp

6

-continued

5	Pulp color before maturity	White (155A, RHS)
	Pulp color at maturity	White (155A, RHS)
	Fruits fall from hands.	Persistent
	Flesh texture	Firm
	Predominant taste	Sweet
	Presence of seed with the source of pollen	Without seeds
	Seed surface	Without seeds
	Seed shape	Without seeds
10	Growth habit of the plant	Upright

The invention claimed is:

1. A new and distinct variety of banana plant named
15 'SH-4199', substantially as illustrated and described herein.
